United States Patent Office

Des. 177,066
Patented Mar. 6, 1956

177,066

PIN

Harry Maximilian Osers, New York, N. Y.

Application June 15, 1955, Serial No. 36,525

Term of patent 3½ years

(Cl. D29—2)

Fig. 1

Fig. 2

Fig. 3

Fig. 1 is a front elevation view of a pin, showing my new design, the fastening element being omitted for convenience of illustration.

Fig. 2 is a side view thereof, and

Fig. 3 is a view from the bottom.

The dominant features of my design reside in those portions shown in full lines.

I claim:

The ornamental design for a pin, as shown and described.
